This technical cross-sectional diagram illustrates a door assembly, likely a double door, featuring a central vertical frame and two side panels. The diagram is annotated with numerous numbers, likely referring to a parts list or patent claims. Key labeled components include:

- 1: Top left corner of the left panel.
- 29: Top right corner of the left panel.
- 81: Middle right corner of the left panel.
- 12: Middle left corner of the left panel.
- 222: A small rectangular component near the center of the left panel.
- 221: A larger rectangular component on the right side of the central frame.
- 92: A rectangular component on the left side of the central frame.
- 91: A rectangular component on the right side of the central frame.
- 217: A rectangular component on the right side of the central frame.
- 93: A small rectangular component on the left side of the central frame.
- 94: A small rectangular component on the right side of the central frame.
- 80: A rectangular component at the bottom left of the central frame.
- 78: A rectangular component at the bottom right of the central frame.
- 95: A rectangular component at the bottom center of the central frame.
- 31: Bottom right corner of the right panel.

UNITED STATES PATENT OFFICE.

JOHN L. C. RORISON, OF UNIVERSITY, VIRGINIA.

AUTOMATIC TALKING-MACHINE.

1,321,852.

Specification of Letters Patent. Patented Nov. 18, 1919.

Application filed August 16, 1915. Serial No. 45,698.

To all whom it may concern:

Be it known that I, JOHN L. C. RORISON, a citizen of the United States, and residing at University, in the county of Albemarle 5 and State of Virginia, have invented certain new and useful Improvements in Automatic Talking-Machines, of which the following is a specification.

My invention relates to the class of disk-10 talking machines or graphophones and pertains primarily to mechanism whereby a plurality of talking machine disks are fed automatically into playing positions. The mechanism is electrically controlled and 15 after the main switch has started the playing of the records, the operator may absent himself entirely. This improved machine will then play record after record, feeding a new needle for each record, and after rendering the last record will automatically begin over again and replay the records continually until the electric power is switched off.

Such construction will be found particularly applicable and valuable in music halls, 25 moving picture theaters, dance rooms, theaters, cafés and in the home.

One important feature of said invention consists in the fact that the necessary mechanical functions which take place between 30 the rendition of each record, start their operation immediately after the last tone of a record just played has been reproduced. Directly after a record has been played, these 35 operations begin, whether the said record be a long one, viz. a record on which the needle grooves extend far from the edge, or a short one, viz. a record with a long or short radius on which there are less needle grooves 40 circulating from the edge toward the center.

Another important feature of the invention consists in the fact that by means of a clock mechanism, the operation of the machine may be begun and automatically 45 stopped at a predetermined time for which the clock was set. In the same manner the machine may also be started at any predetermined time.

Another important feature of said invention resides in the fact that the swing of the 50 sound arm can be utilized for the changing of the sound box needle, and for the making and breaking of the several electric contacts.

The invention further relates to a new and 55 improved means for automatically feeding a

new needle for the playing of each record whereby if there are one or more records in the machine for which soft tone needles are preferred, by a simple operation they may always be automatically fed to the desired 60 record or records.

Regarding the operation of the machine generally, an important feature resides in the fact that by means of a vertically movable carriage, the surface of the record 65 which is in playing position will always be of substantially the same height, that is, for each record which is released from the magazine the rotating table will be lowered the distance of the thickness of the released record and its contact disk, irrespective of the 70 thickness of the record.

The above and other objects and advantages of my improvements will fully appear from the following description taken in connection with the accompanying drawings and be explicitly defined in the appended claims. I wish it understood, however, that this disclosure is illustrative only and that the principle of my invention may be embodied in constructions other than the one specified herein.

In the accompanying drawings forming a part of this specification, similar reference parts are referred to by the same reference 75 numerals.

Figure 1 shows the greater part of my talking machine in side elevation, with the side wall removed;

Fig. 1^a shows the upper part of the same 90 in side elevation, with the side wall removed;

Fig. 2 shows the dogs in plan which release the record from the magazine and one of the record lowering levers, the latter also 95 being thrown out as shown in dotted lines;

Fig. 3 shows a sectional view of the same, showing in dotted lines the movements of the dogs when releasing a record and when the records are being raised back into the magazine;

Fig. 4 shows in plan the record releasing magnets A and the commutators and the brush which carry the current to these magnets;

Fig. 5 shows the handle on the outside of the bearing 17 shown in Fig. 1^a with which to lift the attached mechanism;

Fig. 6 shows my machine in plan on the line 6—6 of Fig. 1^a;

- Fig. 7 shows a part section and a part side view of the sound box;
- Fig. 8 shows a side view of the sound box, this being the side which attaches to the 5 sound arm elbow;
- Fig. 9 shows the lower parts of the sound box in perspective;
- Fig. 10 shows the same in section, showing the eccentric bearing against the needle;
- Fig. 11 shows enlarged part of side elevation, down from line 19 of Fig. 1;
- Fig. 12 shows a part of the platform 7 in plan down from line 12—12 of Fig. 11;
- Fig. 13 shows a part of the platform 8 in 15 plan from line 13—13 of Fig. 11;
- Fig. 14 shows sections of sound arm and its pawl showing relation to tripping assembly when down, the dotted position shows its movement;
- Fig. 15 shows a section of the same except showing the tripping assembly in its upward position;
- Fig. 16 shows the tripping assembly in perspective, with two circuits which are 25 broken and one which is closed when the lever is pushed down by the pawl on the sound arm;
- Fig. 17 shows the clock in plan, in position to turn main switch off;
- Fig. 18 shows the clock in elevation, in 30 position to turn the main switch off, the dotted lines showing position of the clock to turn main switch on;
- Fig. 19 shows a part of the platform 8 in 35 plan from line 19—19 of Fig. 1, showing in dotted lines the position of the sound arm when sound box is receiving a new needle;
- Fig. 20 shows the bottom of the weighted armature assembly, shown in Fig. 1 directly 40 below the magnets A, the dotted lines showing the movement of the arms of the inclosed ring;
- Fig. 21 shows the same armature and its plate in perspective;
- Fig. 22 shows a plan view of the arm assembly which is stationary with respect to the armature assembly of Fig. 20, it is shown in Fig. 1 directly below the armature assembly which is shown in Fig. 21;
- Fig. 23 shows a sectional view of the 50 spring button on the swinging arm assembly of Fig. 22, which is designed to hold these arms either open as when playing or collapsed as when loading;
- Fig. 24 shows the same in fragmentary bottom plan;
- Fig. 25 shows the same parts as Fig. 22 only in perspective;
- Fig. 26 shows in perspective the adjustable fork with the breakers which is used for setting machine for either ten or twelve inch records;
- Fig. 27 shows the insulation and wiring of the same in section;
- Fig. 28 shows the needle changing mecha- nism and magazine in plan, the sound arm being shown in position of just having received a new needle;
- Fig. 29 shows the same in front elevation, together with the mechanism for gently 70 lowering the sound box; in dotted lines a needle is shown entering the sound box funnel, having just passed through the orifice from the needle magazine. In the tube of the left of the magazine are shown half tone 75 needles while in the tube on the right are shown full tone needles;
- Fig. 30 shows in section the box which receives the used needles and the pawls which operate the needle changing mechanism of the sound box; dotted lines show 80 relation of sound box and this said mechanism to these pawls;
- Fig. 31 shows in perspective the pawl which releases the used needle from the 85 sound box;
- Fig. 32 shows in perspective the lever and the pawl which release the contact which is shown released in Fig. 12;
- Fig. 33 shows in elevation the clutch assembly which is mounted on the main shaft of the record lifting motor, shown also in elevation in Fig. 35. Dotted lines in Fig. 33 show the position of the weighted levers when out of engagement with their grooves, 95 the levers are sprung to this position when the motor stops rotating;
- Fig. 34 shows the same in section from the line 34—34 of Fig. 33; and
- Fig. 35 shows the wiring diagram of the 100 machine with representation of the parts to which the wires are connected.
- Certain electro-magnets have been referred to by letters, that is, A being the record releasing magnet, B the magnet that 105 lifts the sound box, C the magnet which causes the sound arm to be sent to the record, and D is the magnet which causes the sound arm to be sent away from the records. The talking machine, in the example of construction shown, is arranged in the usual casing 1 as shown in Figs. 1 and 1^a, with 2, 3, 4 and 5 representing doors in the front of the machine whereby the interior mechanism is 110 made accessible to the operator. The numeral 6 denotes the bottom of the casing 1 and at suitable heights are arranged the platforms 7 and 8 whereby the mechanism is properly supported. The reference character 9 is a plunger pin which catches in the 115 notch 15 and holds the required mechanism up while records are being placed in the machine to be played, while 10 denotes pins and 11 is the slot for the pins 10. 12 is a stop plate against which the spring bears 120 and 13 is spring which pushes against the pins 14 of the plunger pin 9. 15 designates a notch on the upright column 29 into which the plunger 9 fits, and 16 shows wings on the outside of bearing assembly 17 to facilitate 125 130

the raising of the attached mechanism. Journalized in the bearing 17 is the rotating rod 18, the lower end of which is attached to the crossbar 19. Secured to the crossbar 19 by set screws 21 are the upright rods 20. Resting on the top disk 52 is the disk 22 which is held rigid with the rods 20 by the set screws 23.

24 denotes the upper arm of the sliding carriage 26 and 25 the lower arm. This sliding carriage 26 moves on the beam 29, the rollers 27 allowing the said carriage 26 to move easily on the beam 29, and the lower rollers 28 also allowing the said carriage to move easily on the beam 29. 29 is the stationary beam for the carriage 26 to slide on. 30 is the spring which takes up the weight of the carriage 26 and the records which are on the turn-table 47, this spring being supported by the lower bracket 31 which holds beam 29. 32 is an upper bracket which also holds beam 29 with the set screw 33. 34 is a main switch. 35 is a drive motor which rotates the records and 25 attached parts and operates the moving off and on of the sound arm 66.

36 is the pinion of drive motor 35, with which meshes the gear 37. 38 denotes a shaft with which the gears 37 and 40 are 30 rigid by means of set screws 39 and 41 respectively. 42 denotes a bevel gear with which the bevel pinion 40 meshes, 43 denoting the set screw of bevel gear 42. 44 is record drive shaft.

35 45 is the spline in record drive shaft 44. 46 is the bearing on which the turn-table 47 rotates on the bracket 25, and which may be raised or lowered on the shaft 44 and turn with it. 47 is the turntable mounted 40 on the bearing 46.

48 is a sound box assembly, and 49 the needle of said sound box 48.

A record 50 is shown in playing position. 51 is a contact point which is attached to the 45 sound arm 66 and which contacts with the metal disk 52. On the disk 52 is mounted the spring contact 53 to make certain connection with shaft 44.

18' is a brush for the shaft 18 on the 50 bracket 24.

54 denotes the armature of the magnet B. 55 is the bracket for the rod from the armature 54. 56 is the insulated arm to which are attached the contacts 58 and 60. 57 is 55 contact which completes the circuit with contact 58 to keep the magnet B charged, the contact 58 have the same function as the contact 57. The contact 59 on the arm 56 completes the circuit with the contact 60 to

60 cause the sound arm to be sent away from the record. 61 is a bell crank, pivoted at 62, from which rod 63 goes to the sound box. 63 is the rod which extends from the bell crank 61 to the arm 64 of the sound box 56 elbow.

64 is the arm of the sound box elbow 65. 66 is the sound arm.

67 is the lever of the friction gear 71, which is the armature of magnets C and D. 68 is the pivot of the lever 67. 69 is the 70 fork of the lever 67 which collars the bevel friction gear. 70 is the bevel friction gear for sending off the sound arm 66. 70' is the bevel friction gear for sending the sound arm 66 toward the record. 71 is a bevel 75 pinion of the shaft 38 and 72 is a bracket which supports arms 74, 75 and 76 and shaft 38. Splined to the shaft 73 is the bevel friction gear 70. 74 is the upper bracket for the shaft 73 and 75 is the lower bracket for the 80 shaft 73. 77 is a pinion rigid to shaft 73 by means of set screw 79. 78 is the gear with which pinion 77 meshes. 80 is the set-screw of gear 78.

81 is the shaft extending from the socket 85 82 of the sound arm 66 to the bearing 82', also rigid with the gear 78. 83 represents the set screw of the socket 82, and 84 the upright section of the sound channel from the sound arm 66. 84 denotes the upright 90 section of the sound channel from the sound arm 66. The sound channel 84 has the crowfeet 85 at the top thereof, and the elbow 88 has the crowfeet 86 at the bottom thereof. 87 is the pivot which allows the upright section 84 to turn in the end of the elbow 88. 89 is an amplifying horn having the shutters 95 90 at the end thereof.

The shaft 81 has an extension arm 93 which holds the brush 91. At the end of the insulated arc 95 is the metallic plate 92. The arm 93 is held to the shaft 81 by the setscrew 94. 95 is an insulated arc. 96 are the binding posts for the conductors from the magnets A. Holding the brush arms 99 and 102 100 is the bracket 97, and also holding the brush arms 99 and 102 is the axis 98. 100 denotes the upper brush against the commutator 101. 103 is the lower brush of the brush arm 102, and 104 the commutator of the brush 103. 110 105 denotes one of the brackets which holds the magnets A and the commutators to the rod 106. Attached to the knock-out-bearing 111 is the shaft 106 which supports the records in the magazine and the attached parts. 115 107 is the screws which hold bracket 105 to the upright rotating rod 106.

Holding bearing for the cup 110 is the bracket 108. Supporting the cup 110 are the balls 109. The tapering disk 111 is 120 integral with the shaft 106. 112 is a cap which screws on the cone 110. Holding the weight which is on the bearing 109 is the bracket 113.

114 is the armature of the magnets A in 125 which the arm supporting ring 115 turns. Screwed to the armature 114 is the plate 116 held thereto by the screws 117. 118 denote the extending arms of the armature 114. 119 is the tap which holds the rod 120 verti- 130

cally rigid with the arm 118, but allows it to slide horizontally in a slot for the purpose of playing ten inch records when desired.

120 is the movable rod from the arm 118 to the pivot 122 of the lever 121. The lever 121 is pivoted at 123, also to the rod 120 at 122, and to the dog 124 at 125, and to the lower dog 126 at 127. 122 is the pivot of the rod 120 to the lever 121, and 123 is the pivot of the lever 121 to the vertical support 146. 124 is the upper dog of set which is pivoted at 125 to the lever 121. 126 is the dog pivoted to lever 121 at 127. 128 is the roller of the dog 124 and 129 is the roller of the dog 126, and 130 is the lug upon which the dog 124 rides.

131 denotes the roller of record lowering lever 132, and 132 is the record lowering lever which is fixed rigid with the splined shaft 133 by means of the set screw 136. This splined shaft 133 slides through brackets 134 and 135, and tends to compress spring 137 when it slides down through its brackets. 134 denotes the upper bracket of the shaft 133, and 135 denotes the lower bracket of the shaft 133. The weak spring 137 thrusts the shaft 137 back to its normal position after a record has been released from the rollers 131. 138 is the spline of the shaft 133 into which the key 139 fits, said key causing the roller 132 to be thrown from under the record at the right time.

140 denotes the plate which holds the ring 145 in its slot in which it can turn. 141 is the extending arms through which are slots in which ring 145 can turn and to which the plate 140 is screwed. 142 is the holes in the arms 141 into which the winged screw 144 is screwed when it is desired that ten inch records be played. The ring 145 slides through the arms 141 and to which the swinging arms are attached. 146 is the vertical support for the record dropping dogs and the other mechanism which is involved, while 147 denotes the pin which fits in the hole 148 to hold the swinging arms outward and which fits in a respective hole to hold the arms in collapsed position while new records are being placed in the magazine. 148 is the hole in the ring 145 into which pin 147 fits. 150 is a metallic spring to which is attached the pin 147. Holding the spring 150 to the arm 141 is the screw 149.

The case 151 holds the tubes of the needles, said case having the projections 152 upon which the trip 174 operates. 153 denotes an axle upon which is mounted the chamber 151 and the supporting rack 156, which is rigid with the axle 153. 154 is the upper hinged bracket of the axle 153. 155 is a bracket. 157 is a glazed plate which is attached to the side of the casing, and upon which the needles ride until they get over the orifice 168. 158 is the tube of the soft tone needles (shown over the orifice 168),

while 159 is the tube of the full tone needles. 160 is a pin under tension of the spring 164 which fits in one of the twelve depressions of the chamber 151 to hold it in its proper place. 162 is a graduated slide upon which the weighted levers 165 ride, said slide being supported by the bracket 161. 163 is a screw cap which holds the spring 164 against the pin 160. The spring 164 pushes the pin 160 in its respective depression in the case 151. 165 denotes a weighted lever attached to the needle tube at the pivot 166, which rides on the graduated slide 162. 167 is the end of the lever 165 which rests against the second needle in the tube and allows only one needle to escape at a time. 168 is the orifice in the glazed plate 157.

169 is the roller on the end of the sound arm 66 which pushes the lever 170 back, causing the needle magazine to move one space, and allowing a new needle to descend from the tube. The lever 170 is pivoted to the bracket 172 at 171. 172 is the bracket which supports the lever 170. 173 is the spring which tends to hold the arm 170 in its normal position. 174 is a pawl on the end of the lever 170. 175 is a spring which allows the arm 174 to pass projections 152 when it springs back to its normal position. 176 is a one-way pawl for releasing a needle, and is stationary when the arm is leaving the record. 177 is the spring which allows the pawl 176 to flop back as the sound box goes back to the record. 178 is the box into which the used needles fall.

179 is the one-way trip for releasing the ratchet on the lower part of the sound box, and is stationary when the sound arm is moving toward the record but releasable as the sound arm leaves the record. 180 is the spring which allows the trip 179 to flop back as the sound arm leaves the record. 181 is a composition block upon which new needles from the magazine rests until the trip 179 releases the ratchet and causes the new needle to be grasped. 182 is the funnel tube of the sound box, through which a new needle passes when released by the needle magazine. 183 is a tube in the lower part of the sound box into which a new needle goes from the funnel tube 182. 184 is an eccentric lug which is normally pushed against a needle by the spring 187 of the ratchet assembly 186. 185 is a ratchet wheel which is integral with the eccentric lug 184 having teeth 188, into which lever 190 catches. 189 is the pivot of the lever 190. 191 is the spring which tends to push lever 190 against the ratchet wheel 185. 192 is the removable block for inserting eccentric 184 in the assembly.

193 is the upper lug on the carriage 26, which pushes the lever 194 down after the last record in the magazine has been released. 193' is the lower lug on the carriage 130

26 which, when all records have been raised back into the magazine, pushes up the catch 194 and releases the lever 194'. 194 is the weighted catch which holds the lever 194' 5 down until it is released. 194' is a lever pivoted at 195 for raising the tripping assembly 198, while 194^a is a bracket to which weighted catch 194 is pivoted, with a stop to keep it in its normal position. 196 is an 10 insulation block, hinged at pivot 197, upon which tripping assembly 198 is mounted. 198 is graduated lever pivoted at 198'. 199 is the pivot of the lever 198 to the block 196. 200 is the spring which tends to hold 15 the lower end of the lever 198 down to the block 196. 201 is the contact on the lever 198 which closes the circuit with the contact 202 and normally keeps the circuit closed to the contact point 59 on the arm 57. 203 is 20 contact on the lever 198 which closes the circuit with the contact 204 to normally keep the circuit closed to the drive motor 35. The contact 205 is on the lever 198 which closes 25 the circuit with the contact 206 and causes the record lifting motor 234 to rotate. 206 is an overhead contact on the block 196, said contact closing the circuit with the contact 205.

207 denotes a weighted one-way trip pivoted to the sound arm 66 at 208. 209 is a spring-metal lug on the reversible contact 211. 210 is the pivot of reversible contact 211. 211 is the reversible contact normally closing the contact with the contact 216 but opening that circuit and closing one with the contact 212 when the direction of the moving of the sound arm is to be reversed. 213 is a pointed lever which locks the contact 211 against the contact 212. 214 is 30 a spring which holds the lever 213 against the contact 211. 215 is the pivot of the lever 213. 216 is a contact point through which the circuit is normally closed with the contact 211 to keep the current to the point 202. 217 is the rod from the lever 213 to the tripper 218. 218 is tripper which allows the contact 211 to return to its normal position when pushed over by trip 219 as sound arm is returning to record. 219 is a one-way 45 trip which pushes tripper 218 when the sound arm is moving toward the record. 220 is a block to which the trip 219 is hinged. 221 is the arm from the shaft 81 which carries the trip 219. 222 is the set screw 50 which holds the arm 221 rigid with the shaft 81. 223 is an arm from the rod 63 which pushes the pin 224 against the spring 225 and prevents the needle from falling on the record and chipping it. 224 is a plunger 55 pin which is pushed by the projection 223 and which is pivoted to the ratchet wheel 230. 225 is a spring which tends to push the pin 224 against the projection 223. 226 is a pointed plunger pin which is normally 60 pushed against eccentric wheel 230 by the 26 spring 227. 227 is a spring which tends to push the pointed pin 226 against the ratchet wheel 230. 228 is an arm extending from the rod 63 for releasing the ratchet wheel 230 by drawing the pin 226 back. 229 is a 70 plate upon which the sound box lowering device is mounted.

231 is bearing for the shaft 44, and 232 is the lower bearing for the shaft 44. 233 is the felt to absorb vibration of the shaft 44. 75 234 denotes a record lifting motor, and 235 is a pinion on the shaft of the motor 234. 235' is a gear with which the pinion 235 meshes and 235^a is the shaft of the gear 235' and the pinion 244^a. 236 and 237 are 80 the weighted levers pivoted to the shaft of the motor 234. 238 is the weight on the end of the lever 236 and 239 is the weight on the end of the lever 237. 240 is the pivot of the lever 237 to the shaft of the motor 234. 85 241 is the graduated slots terminating abruptly in an extension integral with the pinion 235, into which slots the ends of the levers 236 and 237 lock when the shaft of the motor 234 begins to revolve. 242 is 90 springs which push ends of the levers 236 and 237 out of the slots 241 as soon as the shaft of the motor 234 ceases to rotate.

244 denotes the carriage which lifts up the records and which moves on the slide 95 250. 244' is the rack on the side of the carriage 244 which meshes with the pinion 244^a. 245 is the upper bracket which holds the slide 250. 245' is the bearings of the shaft 235^a. 246 is the lower bracket of the 100 slide 250. 247 and 248 are the upper and lower rollers respectively, of the carriage 244. 249 is the fork from the carriage 244 which straddles the turntable when lifting up records. 249' is rollers upon which records rest as they are being lifted up. 250 is the slide of the carriage 244. 105

251 is the insulated lug which breaks the contact 252 from the contact 253 when the records, which are being lifted, reach the required height. The contact 252 is normally held by the spring against the contact 253, which when broken causes the motor 234 to stop. 253 is a contact which closes 115 the circuit with the contact 252.

254 is an adjustable fork for ten or twelve inch record stops, with circuit breakers for each. 255 is pin which holds fork 254 in position in which it is placed and 256 is pivot and binder post of the fork 254. 257 120 is the insulation of 256 and 254. 259 is the contact point and breaker on fork 254 for use with 12 inch records, and 260 is the contact point on the fork 254 for use with 10 inch records. 258 is the contact point on 125 the fork 254 for use with 12 inch records. 261 is the contact point and breaker on the fork 254 for use with 10 inch records. 262 is the bracket for the contact breaker 259, insulated to 254, said contact 130

262 being held in its normal position by the spring 262'. 263 is the bracket for the contact breaker 261, insulated to the fork 254, said contact 263 being held in its normal position by the spring 263'.

265 is a thumb screw to regulate the speed of the turntable 47, and 266 is an extension of the thumb screw through the platform 7. 267 is a bent shaft extending from the extension 266 to the pad 270 through the bracket 269. 268 is a spring which normally holds the pad 270 against the disk 271' of the governor assembly 271. 269 is the bracket which holds the shaft 267 and its spring 268. The pad 270 puts the brakes on the disk 271' thereby reducing the speed of the turntable 47, if desired. The governor assembly 271 is held by the bracket 272. 271' is the metal disk which is attached 20 to the movable end of the governor assembly 271.

274 is the mechanism of an alarm clock for turning the main switch 34 on and off automatically, and 275 is the shaft of the 25 clock mechanism which partly rotates at the time for which the clock has previously been set. 276 is a lever attached to the shaft 275 and insulated at its striking end. 277 is the pivot of the main switch 34 insulated to 30 the side of the casing. 278 is the slot for clock to be used when it is desired that the switch be turned off and 279 is the slot for clock when it is desired that the switch be turned on. 280 is the pin on the vertical 35 support 146 which holds the dog 126 up while the records are being placed in the magazine.

Having briefly enumerated the several parts of my machine to make the description 40 and specification clear, I have enumerated the operation in the following steps:— After the records and their contact disks have been placed in the magazine, the electric switch turned on and the sound box 45 raised to its upper position, all operations are automatically performed. All operations therefore follow each other in the manner hereinafter set forth:

1. The placing of the records in the magazine, turning on the electric switch and raising the sound box.
2. The releasing of the used needle by the swinging outward of the sound arm.
3. The charging of the magnets which release a record from the magazine.
4. The turning one space of the needle chamber which allows only one needle to be released to the sound box which is at that time directly under the needle magazine.
5. The breaking of the circuit which causes the sound arm to be sent from the record, and the closing of another circuit which causes the sound arm to be sent back toward the record.

6. The releasing of the ratchet which 65 causes the new needle to be grasped.

7. The tripping of a contact breaker which breaks the circuit with the magnet which has been holding up the sound box, this also causing the breaking of the circuit 70 which has caused the sound arm to be brought to the record and the lowering of the sound box stylus to the edge of the record.

8. The releasing to normal position of 75 the pivoted contact which caused the movement of the sound arm to be reversed.

9. The closing of a circuit directly after the last note has been reproduced from the record, which causes the sound box to be 80 raised from the record, this completing another circuit which causes the sound arm to be swung away from the record.

The above operations take place in that sequence until there are no more records 85 in the magazine, when the next operations follow in the manner hereinafter set forth:

10. The raising into the path of a pawl on the sound arm of a contact breaking and making assembly.

11. (After the last record has been played.) The tripping of the contact breaking and making assembly, which breaks the circuits to the drive motor and to the magnet which causes the sound arm to move from the record, and the completing of the circuit to the record lifting motor.

12. The flying out of the weighted levers on the shaft of the record lifting motor which cause the pinion of this motor to be 100 clutched, which sends the record lifting carriage up.

13. The simultaneous releasing to normal position of the contact making and breaking assembly and the breaking of the circuit 105 to the record lifting motor when the records are raised to the required height.

14. The springing of the weighted levers on the record lifting motor shaft out of engagement with the pinion of same, allowing the record lifting carriage to lower itself back to its normal position.

15. The turning off of the main switch at the time for which the clock mechanism has been set.

1. The placing of the records in the magazine, turning on the electric switch and raising the sound box:—As shown in Fig. 1^a, the plunger pin 9 is slightly turned which allows the attached pins 10 to fit in 120 the slot 11 and causes the pin to be pushed against the beam 29 by the tension of the spring 13 which bears on the plate 12 and on the other end against the pins 14 of the plunger pin 9. By means of the rings 16 125 of the bearing 17, as shown in Figs. 1^a and 5, the attached mechanism may be lifted thereby making a break in the record drive

shaft 44 at the top of the record magazine so that records and their contact disks may be placed therein. The said mechanism which is attached to the bearing 17 and 5 raised with it, consists for the most part of the following: the shaft 18 and its cross bar 19 which slide through the shaft 106. The rods 20 which are set in the cross bar 19 by the set screws 21 are also attached 10 to the shaft 18. The disk 22 into which the rods 20 are set by the set screws 23 and which support the weight of the attached mechanism and that of the records on the turn table, except for that which the spring 15 30 bears, are also attached thereto. When the cross bar 19 is raised and reaches the bottom of the knock-out bearing 111, it pushes it out of the collar 110 and raises the mechanism attached to the bearing 111. 20 This mechanism consists of the following: shaft 106, the record releasing magnets A and their commutators 101 and 104 which are attached to the shaft 106 by the bracket 105 with screws 107 as shown in Figs. 1 and 25 4. Also the arm assembly 141 and the record releasing mechanism which is attached to each arm, magnets A, armature assembly 118 which when in its normal position rests on the swinging arm assembly 141, and the 30 attached rods at the end of each arm which control the record releasing dogs.

The upper end of the shaft 44 is splined so that when the magazine is closed it interlocks with the lower end of the shaft 106 35 and rotates the record magazine and the mechanism connected to the shaft 106, the weight of this however being supported through the knock-out bearing 111 which fits into the collar 110 which rotates on the 40 bearings 109 which are set in the cup 108, the collar 110 having the cap 112 screwed on it to prevent its displacement, the bracket 113 supporting the totaled weight.

Also attached to the bearing 17 which is 45 raised are the following: the upper arm 24 of the sliding carriage 26 and its lower arm 25 upon which rests the record turntable 47 upon bearings 46. The carriage 26 slides by means of the rollers 27 and 28 upon the 50 beam 29 which is attached to the casing at the bottom by means of the bracket 31 and at the top by the bracket 32 and held with the set screw 33. The carriage rests on the coiled spring 30 which is of such a 55 strength that it takes the extra weight of the records that are placed upon the turntable 47. When the carriage 26 is raised to the required height the plunger pin which has been allowed to rest against the beam 60 29 snaps into the notch 15 thereby holding all of the raised mechanism up until the records and their contact disks have been placed in the magazine.

The armature assembly of the magnets A

is in the construction shown, formed as follows: In Fig. 20 the bottom plan is shown, the ring 115 with its extending arms is movable in the slot 114 of the armature assembly 118 thereby allowing the swinging arms of the sliding ring 115 to collapse when 65 the arms of the assembly 141 are collapsed, that is, when the records and their contact disks are being placed into the magazine. Fig. 21 shows the armature assembly with its plate 116 and screws 117 in perspective. 70 Fig. 22 shows in plan the construction of the swinging arm assembly 141, the plate 140 screwed to the arms 141 to hold the ring 145 in its slots in which it slides. This assembly is stationary to the shaft 106 and is shown 75 in Fig. 25 in perspective. Fig. 23 shows a section of the pin 147 attached to the arm 141 by the screw 149 and the metallic spring 150, the pin fitting into its hole 148. This pin holds the sets of the swinging arms collapsed while the magazine is being loaded and outward when the machine is operating. This same pin arrangement is shown in bottom fragmental plan in Fig. 24. When 80 the arm assembly 141 is collapsed the armature assembly 118 which is in the construction just above the assembly 141 collapses simultaneously as the rods 120 prevent any arm of either assembly from folding without also folding the arm above or below it 85 as the case may be. If it is desired that ten inch records be placed the vertical supports 146 are pushed in on the assembly 141 and the screws 144 are screwed into the holes 142. The rods 120, at 119, slide in a slot in 100 the arms 141 dependent upon the movement of the vertical support 146. Should other sized records besides 10 and 12 inch be desired to be put in the magazine it can be done by the making of a hole for the screw 105 144 at the required point on the arm 141. When loading the magazine it is necessary to lift up the lower dog 126 of the upper assembly and keep it up until loaded by the 110 insertion of the pin 280.

In order that the necessary operations following the reproducing of each record may take place directly after the last tone of the record has been reproduced, whether the record be long or short (this does not mean 115 whether 10" or 12" but means the variation of the number of needle grooves on a record of either diameter) metal disks of various radii, these radii corresponding to the last few needle grooves of a record, are placed in 120 the magazine, one over each record to which it corresponds and so when the stylus of the sound box reaches the last few needle grooves of the record, a contact will be made between the metal contact disk 52 and the 125 contact point 51 of the sound arm, thus causing the necessary operations to start imminently after the last tone has been reproduced.

from the record. By means of the contact 53 from the disks 52 to the record drive shaft 44 the current is conveyed through the shafts 44, 106 and 18 to the brush 18', and 5 from there through a wire to its respective point.

In the construction shown, the pin 280 is released from under the dog 126 after 10 seven records and their corresponding contact disks have been placed in the magazine and then the rest of the records are placed thereon. The number of records that are to be placed in the magazine before the pin 280 is to be pulled out depends upon the location of the auxiliary record releasing dogs. 15

After the records and their corresponding contact disks have been placed in the magazine, the plunger pin 9 is withdrawn from the notch 15 in the beam 29 and the 20 sliding carriage and the attached mechanism is lowered until the disk 22 rests on the contact disk of the top record in the magazine.

The electric switch 34 is then turned on 25 and the sound box raised in order that it may close the circuits which will cause the sound arm to swing away from the record and the one which will cause the sound box to be upheld until it automatically releases 30 itself. Both of these operations will be fully described hereinafter. When the main switch 34 is turned on it starts the electric motor 35 whose pinion 36 meshes with the gear 37 which is attached to the shaft 38 by 35 a setscrew 39, bevel pinion 40 also being attached to the shaft 38, by a setscrew 41. The bevel pinion 40 meshes with the bevel gear 42 which is attached to the upright splined shaft 44 by a setscrew 43, the shaft 44 rotating the turntable 47 which is keyed in the spline 45, and having the bearings 231 and 232, these being preferably set upon the felts 233 to prevent unnecessary vibration. In 40 the construction shown in Fig. 1 a bevel friction gear is used to send the sound arm away from the records and to bring it back. This assembly is shown constructed as follows: Numeral 71 represents a bevel friction pinion which is attached to the end of 45 the shaft 38 thereby utilizing the record drive power to send off and bring on the sound arm. This construction of the friction gear is also shown in Fig. 35. When the magnet D is charged, it attracts the 50 armature lever 67 which is pivoted to the arm 76 of the bracket 72 as at 68, and whose fork 69 bears against the bevel friction gear 70, which is splined to the shaft 73, against the revolving bevel friction pinion 71. This 55 turns the shaft 73 which is supported by the arms 74 and 75 of the bracket 72, and its pinion 77 which is attached to it by the setscrew 79 meshes with the gear 78 which is attached to the shaft 81 by the setscrew 80, 60 the shaft 81 being set into the socket 82 by

the screw 83 thereby turning the sound arm 66, to the axis of which, the socket 82 is brazed or otherwise attached. Normally the springs of the bevel friction gear hold the bevel frictions 70 and 70' out of engagement with the pinion 71, but when the magnet D is charged it engages with the bevel friction 70 sending the sound arm from the record, and when the magnet C is charged it engages the bevel friction 70' which causes 75 the sound arm to swing back to the record. Other forms of reversible gears may be used but owing to the simplicity, ease of operation and absence of noise, this bevel friction gear (reversible) is employed in the 80 construction shown.

The top of the record drive shaft 44 is splined into its socket in the shaft 106, hence it not only turns the turntable 47, but also the record magazine and the record releasing magnets A and the other attached mechanism. 85 This form of construction enables the records to be released from the record magazine while the turntable rotates thereby saving the time that it takes to stop and start the motor. It also makes it possible for the motor to always rotate the same weight of records—if it were not for this, the weight to be rotated would, as the new records were released from the magazine, be increased 90 and the speed of the turntable would hence be reduced and would thereby make it necessary for the speed of the turntable to be regulated, which besides being trouble would not permit the machine to operate properly 100 and automatically as does this form of construction shown.

In order that the operator may occasionally regulate the speed of the record a governor represented by the numeral 271 supported by the bracket 272 is shown in the construction in Fig. 1. The operation of the speed regulator thus shown is as follows:— The thumbscrew 265 shown at the platform 105 8 of Fig. 1 has its extension 266 held on the end of the bent shaft 267 as is shown in the plan of Fig. 6, the shaft 267 being supported by the bracket 269 and having at its end an arm supporting a pad 270 and holding it against the metal disk 271' of the sliding end of the governor assembly 270, the coil spring 268 normally holding the pad against the disk 271'. When it is desired that the 110 turntable's speed be increased the thumb screw is screwed down and to reduce the 115 speed of the turntable, vice versa. 120

Then automatically follows:

2. The releasing of the used needle by the swinging out of the sound arm: As shown 125 in Figs. 7, 8, 9 and 10 the example of the construction of the sound box and its attached mechanism is represented as follows: The numeral 48 is the sound box proper with the funnel tube 182 extending through it vertically, this tube is broken above the 130

sound box mechanism so that the lower part may vibrate independently of the upper part, 183 being the tube below the break. The numeral 184 represents an eccentric 5 which bears in an upward direction upon the needle, thereby tending to make the needle rigid with the block in which the needle lies. The eccentric 184 is rigid with the shaft upon which the ratchet wheel 185 10 and the lever 186 are mounted, and the spring 187 tends normally to push the ratchet wheel around so that the eccentric 184 will be held against the needle. 188 represents the notches on the ratchet wheel 185 into which the point of the lever 190 15 catches thereby holding the eccentric away from the needles position after the used needle has been released and until the new needle is introduced therein, the lever 190 being pivoted to the block at 189 and being 20 normally pushed against the ratchet wheel by the spring 191, the block 192 being removable for the insertion of the eccentric 184 in the assembly. The numeral 49 represents the needles. 25

As the sound arm travels away from the record the pawl 176 engages the lever 186, as shown in the Figs. 6, 19, 28, 30 and 31, and pushes the eccentric in a downward direction away from the needle, thereby releasing it from the sound box, the lever 190 simultaneously catching the ratchet wheel 185 and locking it until the lever 190 is afterward automatically tripped. The released needle falls into the box 178. Fig. 31 shows in perspective an example of pawl which operates its member lever when the sound arm is leaving the record and which simply flops back when the sound arm is 40 moving toward the record, the spring 177 allowing it to flop and spring back as soon as the lever 186 has passed it on its way back to the record.

3. The charging of the magnets which releases a record from the magazine: As is shown in Figs. 1, 11, 12 and 35, the extending arm 93 moves with the sound arm as it is held rigid with the shaft 81 by the setscrew 94. On the end of the arm 93 is the brush 91 its normal position being against the insulation block 95 but when the sound arm moves away from the record the brush 91 passes from the insulation block 95 to the metallic contact plate 92 thereby closing the 55 circuit with the record releasing magnets A through the binding posts 96 and brushes 100 and 103 of the commutators 101 and 104 respectively, the brushes being held by the spring arms 99 and 102 respectively and the 60 arms being connected to, and insulated with the bracket 97 at the axis 98.

When these magnets are charged they attract their armature assembly 118 and lift it with its projecting arms, to the end of 65 which are attached, in slots, the rods 120,

at 119. The mechanism within and connected with each of the supports, one of which is 146, operate alike and simultaneously, so only one operation will be described within one of the vertical posts. 70 When the armature attracts the arms, the following operation takes place on each of these vertical supports: they all act alike and together so I shall only describe the operation within one of the vertical supports 146. As the rod 120 is drawn up by the arm 118, it turns the lever 121 to which it is pivoted at 122, 121 being pivoted to 146 at 123, as is better shown in Fig. 3, and to the lever 121, at 125, is pivoted the dog 124 which rests on the lug 130, and is pushed out as the lower dog 126 pivoted to the lever 121, at 127, is drawn in, the dog 124 having at its end the rollers 128 and the dog 126 having at its end the roller 129. In Fig. 3 80 the positions of these dogs and rollers as they are when the magnets A are charged are shown in dotted lines, also is shown the position of the dog 126 and its roller 129 when the record lifting device is lifting the 85 records back into the magazine. Fig. 2 shows these dogs and rollers in plan. The operation of the record lowering device shown in the construction is as follows: 90 When the record is released from the magazine, it rests on the roller 131 of the arm 132 which is attached to the shaft 133 by the setscrew 136. The shaft 133 then slides down through the brackets 134 and 135 against the slight tension of the spring 137 95 and when the record falls to the required point the key 139 which fits into the spline 138 of the shaft 133 causes the arm 132 with the roller 131 to be thrown from under the record and the spring 137 draws the arm 100 and its roller back to its normal position which is just below the bottom record in the magazine. The arm 132 is hinged at 136' 105 to allow it to turn up when the record lifter is raising the records back into the magazine, and the spring 136' keeps the roller normally held down. I have described the operation of only one of these record lowering devices but they all operate the same way and at the same time, there being 110 one of them on each of the vertical supports 146.

4. The turning one space of the needle chamber which allows only one needle to be released to the sound box which is at that 115 time directly under the needle magazine: As the sound arm is traveling away from the record the roller 169, as is shown best in the construction in Fig. 28, pushes the lever 170 to the position shown, from the dotted line 120 position. The lever 170 being pivoted to the bracket 172, at 171, and normally held in the dotted line position by the spring 173 which has pivoted near its end the point 174 which is rigid with the lever 170 when being pushed 125 130

by roller 169 but which flops back over the projections 152 as it springs back to its normal position, this position being shown in dotted lines in Fig. 28. The construction 5 of the needle magazine is shown as follows: As in Figs. 28 and 29, the numeral 151 represents the needle tube chamber, to which are attached the projections 152, placed equal distances apart, with which the point 174 10 of the lever 170 engages and turns the chamber one space at a time. The base 151 is mounted on the axle 153 this bearing in the bracket 157 at its bottom and the bracket 154 at its top, the bracket 154 being hinged 15 to the bracket 155 so that the needle chamber and its tubes may be easily removed, although the tubes themselves may be removed from the chamber without raising the bracket 154 by simply lifting them out. The 20 perforated disk 156 is attached to the axle 153 and acts as an upper support for the needle tubes. The numeral 158 represents a tube of soft tone needles which in the position shown is directly above the orifice 168 25 of the glazed plate upon which the bottom needles in the tubes slide prior to reaching the position in which the bottom needle falls through the orifice 168, while 159 represents a tube of full tone needles, the bottom needle 30 in the tube resting on the glazed plate which is supported by the bracket 157. The numeral 160 represents a pin, which under the tension of the spring 164 which is held by the screw cap 163, fits into one of the 35 pressions of the chamber 151 to hold the chamber in its proper place. The numeral 165 represents a weighted lever, one attached to each needle tube at the pivot 166 and having the end 167 which at that point works 40 through a hole in the tube and presses against the second needle in the tube when near and over the orifice 168. These levers 165 ride on the graduated slide 162 which is bracketed by 161. The graduated slide 45 is low and without the reach of the levers 165 when they are over or near the orifice 168 but is graduated to a higher level on the opposite side from the orifice, so that when the levers 165 are turned to the position of 50 over or almost over the orifice 168 they are weighted down and their points 167 press against the second needle of the respective tubes thereby holding all needles up in the tubes except the lowermost one which drops 55 through the orifice 168 into the funnel tube 182 of the sound box which is at this time directly under the orifice 168, then as the chamber is revolved the weighted lever 165 rides upon the slide 162 and soon 60 the point 167 of the lever 165 is brought slowly without the path of the needles in the tube thereby allowing the column of needles to be lowered and the lowermost needle allowed to rest and ride on the glazed 65 plate which is indicated in the numeral 157,

until this tube again comes over the orifice 168 when again only one needle falls through it, and so on. So, as the sound arm travels away from the record, the roller 169 pushes the lever 170 and its pawl 174 engages one of the projections 152 and turns the chamber one space causing one needle tube to be pushed away from the orifice and another to be pushed over the orifice and allowing only one needle to escape from the respective tube 70 into the funnel tube 182 of the sound box. The needle after being released from the magazine slides through the tube 182 of the sound box and the extension 183 of the sound box mechanism, until it rests on the 80 composition block 181, as shown in Figs. 6, 27, 29, 19 and 30. The fresh needles rest on the block 181 until on its swing back to the record, the lever 190 on the mechanism of the sound box is tripped by the pawl 179, 85 thus bringing the point of the lever 190 out of engagement with the ratchet wheel and allowing the eccentric 184 to be thrown against the new needle by the spring 187. The spring 180 of the pawl 179 allows it 90 to flop back as the sound arm swings away from the record, operating its corresponding lever only as the sound arm travels toward the record.

Preferably there are as many needle tubes 95 in the needle magazine as there are records in the record magazine. A machine of this construction allows tubes of soft or other tone needles to be placed in the needle magazine for the desired records in the record 100 magazine. In this manner the desired pre-determined kind of needle will always reproduce the record or records for which they were intended. The many advantages of this construction of needle magazine are 105 evident while a few of the numerous advantages of this construction of needle tube are as follows: The pointed levers 165 allow the column of needles to be gradually lowered and not dropped on the glazed plate 110 beneath them and too they do not slide on the glazed plate long before they fall through the orifice 168 owing to the graduation of the slide 162, this prevents their points from being bruised. By this removable tube system and the construction of the tubes shown the tubes may be taken out of the chamber to be refilled, the levers 165 will form a bottom to them, making it unnecessary to hold a finger at the end of the 115 tube for the purpose of keeping the needles in. The tubes if refilled in this manner may be held at an angle thereby preventing the possible dulling of the points. The needle tubes of the machine may of course be made 120 to accommodate any number of needles, while in the construction shown each tube has a capacity of only a dozen.

5. The breaking of the circuit which caused the sound arm to be sent from the 125 130

record, and the closing of another circuit which causes the sound arm to be sent back toward the record: As is shown in Fig. 11, the arm 221 which is attached to the shaft 5 81 by the setscrew 222 engages the upright spring metal projection 209 which is attached to the reversible contact 211 as is shown in Fig. 12, which is pivoted to the insulation base at 210, and pushes the contact 211 from the contact point 216 to the contact point 212 when the sound arm reaches the extent of its movement, that is, directly after the fresh needle has been released from the needle magazine. After the contact 211 10 has been pushed over on the contact 212 from 216 it is held there until automatically released by pointer lever 213 which is pivoted to the block at 215 and held against the contact 211 by the spring 214. (The releasing 15 of this contact to its normal position which is on the contact point 216 will be described in its order later.) When the contact 211 is pushed from its normal position on 216 the circuit to the magnet D is broken 20 as is shown in Fig. 35 and the bevel friction 25 70 of the reversible friction gear is thrown into neutral by its springs. This causes the sound arm to stop moving but as soon as 211 contacts with 212 the magnet C is charged 30 and the bevel friction 70' is caused to mesh 35 with the bevel pinion 71 of the shaft 38 and this sends the sound arm back toward the record. The reversible friction assembly is supported by the bracket 72 and the bevel frictions 70 and 70' are splined to the shaft 73 which is bracketed to the bracket 72 by 40 the arms 74 and 75. The bevel frictions 70 and 70' are preferably made in one piece and are collared to the fork 69 of the lever 67 which is pivoted to the bracket 76 at 68 and held out of engagement with the bevel pinion 71 by the springs which are behind each of them.

6. The releasing of the ratchet which 45 causes the new needle to be grasped: When the sound arm is moving to the record and while the new needle is in its position in the sound box and sliding on the composition block 181 the lever 190 shown in Figs. 7, 8, 50 9, 10 and 30, is tripped by pawl 179 which releases the ratchet wheel 185 shown in Fig. 9, and allows the eccentric 184 to be sprung against the fresh needle as is shown in Fig. 10.

55 7. The tripping of a contact breaker which breaks the circuit with the magnet which has been holding up the sound box, this also causing the breaking of the circuit which has caused the sound arm to be brought to 60 the record, and the lowering of the sound box stylus to the edge of the record: Fig. 26 shows in perspective a form of adjustable fork with its contact breakers for 10" and 12" records, the position of which when set 65 for 12" records being shown in plans of

Figs. 6 and 19, and the wiring of which is shown in Fig. 35. In Fig. 26 the stem of the device shown is represented by 254, with its handle and locking pin 255. The numeral 256 represents its pivot and binding 70 post and 257 the insulation between it and the surroundings as shown in Fig. 27. The contact breaker for use with 12" inch records is represented by 259, pivoted and insulated to 254 by 262, 258 being the contact 75 point which it normally rests on and from which it breaks its contact when tripped and springs back as soon as tripped, by the tension of the leaf spring 262'. The contact breaker for use with 10" records is represented by 261, pivoted and insulated to 254 by 263, the contact point 260 being the one on which it normally rests and from which it breaks its contact when tripped, and which is sprung back by the spring 263' after being 80 tripped.

After the sound arm has traveled back to the edge of the record, its one-way trip 259' which extends out from the sound arm and is bent down in order that it can trip its 90 contact breakers on the fork 254 which is preferably mounted below the path of the arm, trips the contact breaker 259 (if set for 12" records). When either of these contact breakers 259 or 261 are tripped, the circuit to the magnet B (the magnet on the sound arm which holds up the sound box) is broken, which allows the sound box to be 95 released. Immediately after this circuit is broken, the contact point 59 attached to the 100 armature of this magnet B lifts off of its contact point 58, thereby breaking the circuit to the magnet C (the magnet which causes the sound arm to be sent to the record) this causing the sound arm to stop 105 moving whereupon the sound box is lowered and the stylus allowed to rest in one of the grooves on the edge of the record. The sound box is lowered by a device, the construction of which is shown in Fig. 29, it 110 being operated as follows: The arm 223 which is attached to the rod 63 pushes in the plunger pin 224 against the tension of the spring 225 thereby turning the ratchet wheel 230 which is held around by a pointed pin 115 226 under the tension of the spring 227 until the sound box is again lifted up when the arm 228 which is attached to the rod 63 strikes the pointed pin 226 and thereby releases the ratchet wheel 230. A device similar to the construction shown will lower the needle and the sound box gently and prevent the point from chipping the record as might have been the case were a lowering device not employed. The device in the construction shown is preferably mounted on a plate 120 229 and this attached to the sound arm. Other forms of this device may be used but the principle is shown very clearly by the assembly here represented.

The above mentioned contact breakers 259 and 261 need only to be tripped for about a second, for when the circuit to the magnet B is broken the contacts 60 and 59 are separated, as the point 59 is operated by the armature 54 of the magnet B and this breaks the circuit to the magnet D (the magnet which causes the sound arm to be sent toward the record) and after the contact 59 has been lifted off of the contact 60 the contact breakers may be sprung back to their normal position and the contacts formed with their members for when the armature 54 is released from the magnet B this magnet cannot be charged again until the record which is then in playing position, has been reproduced.

8. The releasing to normal position of the pivoted contact which caused the movement 20 of the sound arm to be reversed: As is shown in Figs. 11, 1 and 35, the arm 221 which, when the sound arm reached the extent of its path, pushed the pivoted contact 211 from the contact 216 over on 212 (and which was held on the contact 212 by the pointed lever 213) has hinged at its end 220 the pawl 219, preferably of spring metal, which pawl, as the sound arm travels back to the record, trips the tripper 218, which by means of the 25 rod 217, releases the pivoted contact 211 by drawing the point of the lever 213 out of the notch thereon. When pivoted contact 211 is thus released it goes back to its normal position, which is in contact with the point 30 216 and is ready to be turned by the arm 221 the next time the sound arm travels outward. As is shown in Fig. 32, the pawl 219 which is hinged to the arm 221 at 220, is of such a construction as to allow it to pass 35 over the tripper 218 of Fig. 11 as the sound arm moves outward from the record.

9. The closing of a circuit directly after the last note has been reproduced from the record, which causes the sound box to be raised from the record, this causing another circuit which causes the sound arm to be swung away from the record: As mentioned and described above, each record is placed in the magazine and above it and placed in 45 the magazine after it is a metal contact disk whose radius approximately corresponds to that of the innermost needle grooves of the record upon which it is placed. These metal contact disks are represented by the numeral 52, one of them being also shown on the record 50 which is in playing position in Fig. 1. Immediately after the last note has been reproduced from this record which is in playing position, the contact point 51 50 which is insulated to the sound arm 66 as is shown in Figs. 1, 6, 19, 28 and 35, makes contact with the contact disk 52 and completes the circuit to the magnet B through the shafts 44, 106 and 18 and the brush 18'. This 60 magnet B when charged attracts its armature 54 and by means of the rod 63 which through the bracket 55 connects the bell-crank 61 pivoted at 62 with the arm 64 of the sound arm elbow 65, raises the sound box and its stylus from the needle grooves 70 of the record.

When this magnet B is charged it attracts the armature 54 to whose insulated arm 56 is attached the contact points 57 and 59. The point 57 makes contact with the contact 75 58 which completes a second circuit to the magnet B and keeps it charged until the circuit is broken by the circuit breaker 259 or 261 of the 10" or 12" record setting fork 254 as is shown on the wiring diagram, Fig. 80 35. The contact point 59 which is also attached to the armature 54 of the magnet B makes contact with the point 60, this completes the circuit to the magnet D which causes the bevel friction 70 to mesh with the 85 bevel friction pinion 71 thereby sending the sound arm away from the record. These contacts 59 and 60 stay in contact with each other until the magnet B is discharged when, of course, they are separated. The circuit 90 however which they form is broken when the pivoted contact 211 is pushed from the contact point 216 by the arm 219 of the shaft 81, and the contacts 57 and 59 are separated from the contact 60 and 58, respectively, a 95 little previous to the time that the pawl 219 of the arm 221 trips the tripper 218 as shown in Fig. 11, which allows the pivoted contact 211 to be sprung from the contact 212 to its normal position on the contact 100 point 216, as is shown on the wiring diagram Fig. 35.

The said sound arm 66 as shown in Fig. 1 is supported at its bottom by the shaft 81 which is socketed to it and which at its bottom is journaled into the bearing 82'. As shown in Figs. 1 and 1^a the sound channel is represented as follows: The numeral 65 is the elbow of the sound arm 66 to which the sound box is attached and 84 is the upright amplifying channel which is a part of the sound arm 66 and whose skeletal cross bar 85 is pivoted to the skeletal crossbar 86 of the elbow 88 of the amplifying horn 89 by the pivot 87, amplifying horn 89 having 110 115 at its mouth, the adjustable series of slats 90 whereby the volume of sound may either be increased or diminished.

The above operations take place in that sequence until there are no more records in 120 the magazine, when the next operations follow in the manner hereinafter set forth:

10. The raising into the path of a pawl on the sound arm of a contact making and breaking assembly: As the last record is released from the record magazine, the disk 22 is lowered to the point on the shaft 44 that the bottom of the last record was previously, that is, the carriage 26 is lowered until it rests on its bumper which is at the 125 130

extremity of its passage downward. When the carriage 26 is being lowered to this point its lug 193 which is shown in Figs. 1, 6, 13 and 19 pushes down the lever 194' which is also shown in Fig. 11 pivoted at 195, and as this lever is pushed down the other end of it pushes the tripping assembly up which raises the graduated lever 198 in the path of the pawl 207 which is pivoted to the 10 sound arm at 208, as is shown in Figs. 11, 13, 14 and 15, the assembly itself being shown in perspective in Fig. 16. When the record is being released from the magazine, the sound arm is outward from the 15 record so the lever 198 thus raised into the path of the pawl 207 is not to be pushed down by it until the last record which has just been released, has been played, hence the pawl 207 is pivoted to the sound arm 20 at 208 and is of such construction that it will pass over the lever 198 and not push it down as the sound arm swings over to the last record prior to its reproduction, as is shown in Figs. 14 and 15. When the 25 lever 194' is pushed down by the lug 193 on the carriage 26, it is held in that position by the weighted lever 194 which is pivoted to its bracket 194^a which has a stop on it to keep the weighted lever in its normal position as is shown in Figs. 11 and 13. This 30 weighted lever 194 locks the lever 194' down until the lever 194 is released by the lower lug 193' of the carriage 26.

11. (After the last record has been played). The tripping of the contact breaking assembly, which breaks the circuits to the drive motor and to the magnet which causes the sound arm to move from the record: After the last record from the magazine has been reproduced, the sound arm travels away from the record as usual and the hinged pawl 207 thereon as shown in Fig. 15, pushes down the lever 198 as is shown more especially in Fig. 16. When 45 this lever 198 which is pivoted to its base 196 at 199 is pushed down, the contact 201 is raised from its member contact 202, the contact 203 is raised from its member contact 204, and the contact 205 completes a 50 circuit with its member contact 206 which is preferably hung over the contact 205 and mounted on the base 196. When the contact 201 is raised from its member contact 202, the circuit to the magnet D is temporarily 55 broken, this causing the movement outward of the sound arm to stop when it will be brought to a standstill while the pawl 27 of the sound arm is engaging the lever 198 as shown in Fig. 15, the wiring of this assembly being shown more especially in Fig. 35. When the contact 203 is raised from its member contact 204, the circuit to the record 60 drive motor 35 is temporarily broken, thus causing the rotating support 47 and the records and disks thereon to stop rotating.

When the contact 205 is raised into contact with its member 206, the circuit to the record lifting motor 234 is closed whereupon its shaft and attached parts as shown more especially in Figs. 33 and 34, begin to revolve. 70

12. The flying out of the weighted levers on the shaft of the record lifting motor which causes the pinion of this motor to be clutched, which sends the record lifting carriage up: In the construction shown of this modified clutch assembly in Figs. 33 and 34, the numerals 238 and 239 represent weights on the levers 236 and 237 respectively, which levers are attached by pivots 240 to the shaft of the motor 234 and the ends of which are on the springs 242 normally held (when motor is not running) out of the graduated slots of the extension 241 of the loosely mounted pinion 235, and which is integral with it, this pinion and its extension turning with the motor when clutched by the ends of the levers 236 and 237. Hence when the shaft of the motor 234 starts revolving, centrifugal force sends the weighted ends of the levers outward, and this in turn causing the other ends of the levers to be pressed inward into the graduated grooves of the extension 241 of the pinion 235 thereby locking the pinion 235 to the shaft and rotating it. This clutch is of such a construction that the pinion 235 of the motor 234 will always turn when the shaft of the motor turns and further will allow the record lifting carriage 244 to descend to its normal position after having raised the records up into the magazine, without having to rotate the shaft of the motor and its more or less comparatively heavy armatures, but simply rotate the pinion 235 which is loosely mounted on the shaft of this motor. 95

As shown in Figs. 1, 6 and 35, the pinion 235 which is clutched by the assembly indicated by its pivot 240 mounted on the shaft of the motor 234, meshes with the gear 235' which is mounted on the shaft 235^a, the shaft 235^a having bearings 245' and also having mounted upon it the pinion 244^a which meshes with the rack 244' which is mounted upon the side of the record lifting carriage 244, thereby lifting the carriage, it rolling on its slide 250 which is bracketed at its top by the bracket 245 and at its bottom by 246, by means of its rollers 247 and 248. To the carriage 244 is preferably cast, the fork 249, which as it is raised upward, straddles the turntable 47, thereby lifting the records thereon by allowing them to rest on the rollers 249' of the record lifting 110 fork 249. 115

As the records are being lifted into the magazine they push the roller 131 up on its hinge 136' which by means of its spring 136^a flops back after the records are raised into 120 125 130

the magazine. They also push the dog 126 as is shown in Figs. 2 and 3, up between the rollers 128 of the slotted dog 124, and after the records are raised to the required height 5 in the magazine these dogs fall back to their normal positions. As the rollers of the dog 124 lie without the radius of the records which are being raised, they are left untouched as the records pass into the magazine, that is, they retain their normal position except when being operated by the magnets A.

13. The simultaneous releasing to normal position of the contact making and breaking assembly and the breaking of the circuit to the record lifting motor, when the records are raised to the required height: 15 When the records are raised up into the magazine, the disk 22 which rests upon the contact disk 52 of the top record, is also raised and this raises the carriage 26 and the other mechanism which is dependent upon the movement of the disk 22. As soon as 20 the records are raised to the required height 25 in the magazine, the lug 193' on the carriage 26 as shown in Figs. 1, 6 and 19, and more especially in Fig. 13, pushes up the weighted locking lever 194, shown in Fig. 11, thereby releasing the lever 194' which in 30 turn lowers the contact breaking and making assembly which is pivoted at 197 down to its normal position as shown more especially in Figs. 11 and 14. When this is lowered, the lever 198 pivoted thereon at 199 35 is lowered out of the path of the pawl 207, thereby allowing the sound arm to continue its movement outward from the record. For when this assembly is lowered, the spring 200 brings the lever 198 to its normal position and the contact 201 again forms a circuit through its member contact 202, which charges the magnet D and causes the sound arm to be sent from its position which was over the lever 198 of the said assembly, outward from the record, and when the contact 203 again completes the circuit through its member contact 204 to the record drive motor 35, the record support 47 has again begun to rotate, and when the contact 205 is 45 lowered from its member contact 206, the circuit to the record lifting motor 234 is broken. Almost simultaneously with the lowering to normal position of the contact breaking and making assembly, the lug 251 50 of the record lifting carriage, as is shown in Figs. 1, 6 and 35, trips the spring-contact (auxiliary) 252, it temporarily breaking the circuit with its member 253 which also breaks the circuit to the record lifting motor 234. It will be noted on the wiring diagram of Fig. 35 that this breaks the same circuit that is broken by the contacts 205 and 206. This circuit breaker 252 is preferably shown 60 in the construction as a safety device to keep 65 the carriage from rising higher on the slide

250 than it should. After the circuit to the record lifting motor is broken, the following operation takes place:

14. The springing of the weighted levers on the record lifting motor shaft out of engagement with the pinion of the same, allowing the record lifting carriage to lower itself back to its normal position: When the shaft of the motor 234 ceases to revolve, the springs 242 as is shown in Figs. 33 and 34, 70 push the ends of the weighted levers 236 and 237 out of engagement with the extension of the pinion 235, thereby releasing this extension from the clutch of the ends of the said levers and the pinion is therefore allowed to 75 revolve free of the shaft of the motor, and the grooves in the extension 241 of the pinion 235 are graduated from the abrupt ends upon which the ends of the said levers catch, to level of the outer radius of the 80 extension as is shown in Fig. 33, thereby allowing the ends of the said levers to slide out smoothly and quickly. When the ends of the levers 236 and 237 are sprung out of 85 engagement with the extension, the record lifting carriage is allowed to descend without revolving the idle motor, but only rotating the pinion of the same, which is not clutched and is hence free to rotate on the 90 shaft of the motor 234 as its axis. 95

15. The turning off of the main switch at the time for which the clock mechanism has been set: When the hands of the clock 274 (Figs. 17 and 18) which for turning the main switch off is placed in the slot 278, 100 reach the time for which the clock mechanism has previously been set, the shaft 275, which also has been set or rather wound, revolves partly, its arm 276 with its insulation projection pushes downward on the knife of 105 the main switch 34, it being pivoted to the side of the casing at 277, thereby turning off the electric current and stopping the machine. The slot 279 on the other hand is used when it is desired that the machine be 110 started at a set time, when the clock mechanism operates in the same manner only acting on the lever or knife at its other end, as is shown in dotted lines in Figs. 17 and 18, thereby pushing the knife into its contact 115 and starting the machine.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire 120 to have it understood that the device shown is merely illustrative and that such changes 125 may be made when desired as fall within the scope of the appended claims.

Having thus described this invention what 130

I desire to claim and secure by Letters Patent is:—

1. The combination with a cabinet and a motor driven turntable supported therein, of 5 a phonograph record magazine supported above the turntable, means associated with the magazine for allowing the records to be placed upon the turntable one at a time, a vertical standard arranged in the cabinet, a 10 vertically movable carriage mounted on the standard, a forked member carried by the carriage adapted to engage the records to carry the same to the top of the cabinet, means for raising the carriage, and means 15 for allowing the carriage to return to its normal position.

2. The combination with a cabinet and a motor driven turntable supported therein, of a phonograph record magazine supported 20 above the turntable, means associated with the magazine for allowing the records to be placed upon the turntable one at a time, a vertical standard arranged in the cabinet, a vertically movable carriage mounted on the 25 standard, a forked member carried by the carriage adapted to engage the records to carry the same to the top of the cabinet, a rack bar secured to the carriage, a motor arranged in the cabinet, gearing connecting 30 the motor and the rack bar, and electrically controlled means for stopping the motor when the carriage has reached the limit of its upward movement whereby the carriage is permitted to return to its normal position. 35

3. A mechanism of the character described including a turntable, a phonograph record magazine supported above the turntable, record engaging dogs carried by the 40 magazine, electromagnets mounted above the magazine, an armature for the magnets carried below the same, rods secured to the ends of the armature having their lower ends operatively connected with the record 45 engaging dogs, means for closing an electrical circuit whereby the armature is moved upwardly thereby disengaging certain of the dogs from the bottom record to permit the same to fall on the turntable and engaging 50 the other dogs with the record next in order.

4. The combination with a motor driven turntable and means for placing talking machine records thereon, one at a time, and 55 a talking machine sound mechanism, of a plate carried by the sound arm, electromagnets, a bell crank lever mounted upon the plate, the armature of said magnets being connected with one end of the bell crank, an 60 arm connected with the sound box, a rod connecting the arm and the bell crank, and means for closing the circuit whereby the armature is attracted thereby raising the sound box off the record.

65. 5. The combination with a cabinet and a

motor driven turntable supported therein, of means for successively placing the phonograph records upon the turntable one at a time, a vertically movable forked member mounted in the cabinet for carrying the records to the top of the cabinet after they have all been played, means for stopping the forked member after it has reached the top of the cabinet whereby it is permitted to return to its normal position.

6. In a phonograph, a cabinet, a motor driven turn-table, a plurality of record lowering arms, said arms being adapted to place the record to be played in playing position during the rotation of said turn-table, and means for returning said record lowering arms to their normal positions during the rotation of said turntable.

7. In a phonograph, a cabinet, a motor driven turn-table, a record lifting fork, means for raising the record lifting fork during the rotation of the turn table, and means for lowering said record lifting fork to its normal position during the rotation of the turn table.

8. In a phonograph, a cabinet, a motor driven turn-table, a record carrying magazine, an electrically charged turn-table drive shaft, said drive shaft being separable at its upper position from the remainder 95 thereof to permit easy insertion of the records into said magazine, a plurality of record lowering arms, said arms being adapted to place the record to be played in playing position during the rotation of said turn-table, and means for returning said record lowering arms to their normal positions during the rotation of said turn-table.

9. In a phonograph, a cabinet, an electrically driven turn-table, a record carrying magazine adapted to receive a plurality of records, means for transmitting successively the records from the magazine to the turn-table, means for removing all the records from the turn-table during the rotation of 105 the turn-table, electrically operated means for lifting the tone arm from the record immediately subsequent to the playing of the record, means for returning the tone arm to a normal position immediately subsequent to the disengagement of the needle from the turn-table, a rotatable needle carrying magazine, and means for transmitting needles successively from said needle carrying magazine to the sound box of the tone arm 110 immediately subsequent to the returning of the tone arm to a normal position.

10. In a phonograph, a motor driven turn table, a record carrying magazine, means for retaining a plurality of records suspended within said magazine above said turn table, a movable tone arm having a sound box, means for lowering successively the records upon said turn table during the rotation thereof, electrically operated means 125 130

for lifting the sound box from said records immediately upon the completion of the playing thereof, means for spacing the records from each other, the electric circuit of said electrically operated means being completed through said spacing means.

11. In a phonograph, a motor driven turn table, a record carrying magazine, means for retaining a plurality of records suspended within said magazine above said turn table, a movable tone arm having a sound box, means for lowering successively the records

upon said turn table during the rotation thereof, electrically operated means for lifting the sound box from said records immediately upon the completion of the playing thereof, means for spacing the records from each other, the electric circuit of said electrically operated means being completed through said spacing means, and means for returning the tone arm to a normal position subsequent to the lifting of the sound box from the records. 15 20

JNO. L. C. RORISON.
